UNITED STATES PATENT OFFICE.

RICHARD C. BEATTY, OF BUFFALO, NEW YORK.

DISPLAY DEVICE.

1,079,097.

Specification of Letters Patent. Patented Nov. 18, 1913.

Application filed April 22, 1912. Serial No. 692,867.

To all whom it may concern:

Be it known that I, RICHARD C. BEATTY, a citizen of the United States, residing at Buffalo, in the county of Erie and State of New York, have invented a new and useful Improvement in Display Devices, of which the following is a specification.

This invention relates to display devices which are intended to be used principally for advertising purposes and which are placed in windows and other conspicuous places to attract attention to articles which are displayed thereon.

The objects of this invention are to provide a display device of this character of simple and inexpensive construction in which the article to be displayed is securely supported by the device in a prominent position at the front thereof, where it will readily attract attention, and to construct the device so that it can be collapsed when not in use, and so that when the device is in its display position, the article displayed therein will interlock with portions of the device to hold the article in place and to prevent the device from being accidentally collapsed.

In the accompanying drawings: Figure 1 is a perspective view of a display device embodying the invention, showing the same in its display position with an article in place therein. Fig. 2 is a fragmentary front elevation thereof, on an enlarged scale, the article being shown in dotted lines. Fig. 3 is a fragmentary side elevation thereof, on an enlarged scale. Fig. 4 is a perspective view of a device of modified construction. Fig. 5 is a fragmentary front elevation thereof, on an enlarged scale, the article being shown in dotted lines. Fig. 6 is a perspective view of another modification thereof. Fig. 7 is a fragmentary front elevation thereof, on an enlarged scale, the article being shown in dotted lines.

Like reference characters refer to like parts in the several figures.

The display device, in general terms, comprises two panels, preferably of similar shape, which are hinged or otherwise connected together along one edge and in their display position extend at an angle to each other so that they will stand upright without the assistance of additional supports.

The panels, at their adjoining edges, are provided with connecting cut-away portions

which form an opening which extends transversely across the joint between these edges, and the article to be displayed is adapted to be inserted into this opening with a considerable portion thereof projecting outwardly beyond the panels. The walls of the panels which form the edges of the opening are arranged to grip the article and hold the same firmly in place therein, while at the same time the article in turn tends to prevent the panels from being accidentally removed to a position in which they will collapse.

In the particular form of display device shown in Figs. 1-3, A A represent the upright connected panels which are formed of card-board or other suitable material, and stand at an angle to each other so as to support each other in their upright display position. These panels may be connected together at their adjoining edges by any suitable means, such as canvas hinges (not shown), which will permit them to be folded open each other when not in use. Both panels are provided at their adjoining edges with cut-out portions or openings B B which open into each other across the joint between the edges. Each opening has inclined top, rear and bottom edges b b' and b" which are adapted to engage the top, rear and bottom sides of a rectangular box C or other article which is received in the opening at an inclination with its bottom projecting outwardly beyond the bottom edge b". The top edge b of each opening is provided with a downwardly inclined retaining portion b' which overlies the upper outer edge of the box C, and the bottom edge b" is inclined upwardly and overlies the lower inner edge of the box, so that the box is securely held in place in the opening by the edges b' and b" and the portions of the edges b' and b which are adjacent to the edges b' and b" respectively. The bottom edges b" of the openings upon which the box or other article rests extend at an angle to each other and thus form an extended base or support for the article and the top and rear edges of the openings engage the article on opposite sides of the center thereof. The edges of the two openings B B thus embrace the box C on opposite sides of its center and interlock with the sides of the box so that the box is securely held in place in the opening, and its

sides tend to prevent the panels from being accidentally moved out of their angular position. The two openings being provided with upper and lower portions which extend toward each other so as to overlap or overhang the upper and lower edges of the article, prevent the article from being lifted out of the device when in its display position. The box or other article is inserted 10 endwise into the openings when the panels are in their partially folded position. The panels are then opened to their display position, in which the edges of the openings snugly engage the sides of the box.

15 To Figs. 4 and 5, a modification is shown in which the panels are provided with connecting cut-out portions or openings D and E which are shaped to receive and retain a box F of different form and to support the same in an inclined position on the device. The opening D has inclined rear edges d and d' which are adapted to engage the rear sides of the box, and top and bottom edges d² and d³ which extend toward each other 20 and are adapted to overhang or overlap the upper and lower corners of the box. The opening E has similar inclined rear edges e and e' and overhanging top and bottom edges e² and e³ and also has an end edge e⁴ 25 at the inner end of the opening against which the lower end of the box F is adapted to rest with its inner corner projecting through the opening.

In the modification shown in Figs. 6 and 35 7, the panels are arranged to display the article on the inner side of the angle between them, instead of on the outer side thereof as in the other construction. In this construction, G and H represent the connecting cut-out portions or openings in the 40 panels. The opening G has five edges g, g', g², g³ and g⁴, of which the edges g, g', g² and g³ are adapted to engage the four sides of a rectangular box I which is to be displayed.

45 The edge g⁴ at the end of the opening is adapted to engage the end of the box. The edges g and g² are inclined toward each other so as to overlap the upper and lower corners of the box and hold the same in the opening. 50 The opening H has upper and lower edges h and h' which are adapted to engage the sides of the box adjacent to the inner edge thereof which projects through this opening, and an end edge h² which engages the end 55 of the box and assists in holding the same in place therein. The article when in place in the opening is held from endwise displacement therein in either direction by the two end edges g⁴ and h². The engagement 60 between the two end edges and the ends of

the box also prevents the angular displacement of the two panels toward each other.

In all of these constructions, the connecting cut-out portions of the connected panels form an opening which extends across the 65 angle or joint between the panels and is adapted to receive the article to be displayed, and this opening is so shaped that its edges will embrace the article and interlock with the sides thereof so as to hold 70 the article securely in place and prevent the panels from moving out of their angular relation with each other.

The panels are preferably provided with some suitable pictorial representation which 75 is associated with the article to be displayed so as to give the appearance of holding the same. Such a representation is shown in Figs. 1-3, in which each panel is provided with the representation of an eagle having 80 one claw extended and associated with the opening in the panel in such a manner as to give the appearance of grasping the article which is placed in the opening. This has the immediate effect of directing attention to the article which is displayed and making this article the central and prominent feature of the device.

I claim as my invention:

1. A display device comprising two connected panels which extend at an angle to each other and which have portions which are cut away adjacent to the connected edges of said panels to form an opening crossing the connecting angle between said panels 95 and adapted to support an article therein, said opening having edge portions which embrace the article and extend toward each other in front of the article, whereby the article is retained in the opening and holds 100 the panels in angular relation to each other, substantially as set forth.

2. A display device comprising two connected panels which extend at an angle to each other and are provided with connecting 105 cut away portions which form an opening crossing the connecting angle between said panels and adapted to support an article therein, said opening having edge portions against which the rear side of the article 110 bears, and portions which overhang the upper and lower edges of the opening for holding the article therein, substantially as set forth.

Witness my hand, this 19th day of April, 115 1912.

RICHARD C. BEATTY.
